UNITED STATES PATENT OFFICE.

ELISE MANNEL, OF SAN FRANCISCO, CALIFORNIA.

DESIGN FOR A DOLL.

Application filed December 27, 1926. Serial No. 20,157. Term of patent 3½ years.

To all whom it may concern:

Be it known that I, ELISE MANNEL, a citizen of the United States, and a resident of the city and county of San Francisco and State of California, have invented a new, original, and ornamental Design for a Doll, of which the following is a specification, reference being had to the accompanying drawings, forming part thereof.

Fig. 2 is a reverse view thereof.

I claim:

The ornamental design for a doll, substantially as shown.

In testimony whereof I have hereunto set my hand.

ELISE MANNEL.
